UNITED STATES PATENT OFFICE

JOSEPH MERLE, OF NEWARK, NEW JERSEY, ASSIGNOR TO MERLE CENTRIFUGAL PROCESSES, INC., OF NEW YORK, N. Y., A CORPORATION OF NEW YORK

PROCESS AND MACHINE FOR CENTRIFUGALLY EXTRUDING AND CASTING SUBSTANCES

Application filed September 4, 1926. Serial No. 133,588.

The present invention relates to processes and machines for compressing, treating, separating, purifying, smelting, melting, working, casting and extruding fluid, liquid, plastic, molten, lump and setting substances, mixtures, compositions, ores, minerals, metals and alloys and to the machines for carrying out such processes. More specifically, the present invention relates to an improvement in the processes and machines for working substances and metals by gyrating and projecting them disclosed in my Patent No. 1,657,132 granted January 24, 1928.

Other objects will be apparent from the following description taken in connection with the accompanying drawings, in which:

Fig. 27 is a vertical sectional view of still another form of gyratory casting machine.

Fig. 28 is a vertical sectional view of a further modified form of gyratory casting machine.

Science shows that the universal gyratory motion is reproduced within the minutest components of the atom of matter and from it is derived their cohesive energy and actual stable or relatively stable conditions, atomic constitution, molecular structure and physical, chemical and other characteristics and properties and any variation of it imparts a modification and transformation or disintegration of these elements by changing their actual dynamic and static equilibrium conditions. It is an object of this invention to use that basic central force to work and transform as many substances, materials, ores, minerals, metals and alloys as possible and as required.

Consequently, the general object of this invention and of the processes and machines hereinafter described and claimed is to gyrate under regulated acceleration and project continuously or intermittently any mass or flow of one or more substances, mixtures, compositions, ores, minerals, materials, metals or alloys in a fluid, liquid, plastic, molten or lump condition or any physi-

- cal state in which they can be submitted to gyratory motion or combined gyratory and translatory motions and also when possible more especially when the mass or flow of substances, mixtures, compositions, ores, minerals, materials, metals or alloys is forced to pass from one physical state to one or more of the adjacent states, such as solid, liquid, gas or dissociation, thereby to take full advantage of the break in the equilibrium conditions as well as of the change in the molecular and atomic cohesion to produce and generate the following within the mass or flow treated:
15. 1. A high internal pressure and stress or stresses which can be uniformly regulated and distributed and of any regulated magnitude and acceleration.
2. One or several intermolecular or atomic motions, rectilinear, curvilinear, gyratory and combined gyratory and translatory motions, of any desired ratios of intensity and magnitude, generating any kinetic energy desired and creating one or various intermolecular or atomic sliding, shock, vibrating, swaging, separating, dissociating and other actions of regulated magnitude and acceleration.
3. Submitting, if desired, the mass or flow treated, at the same time, to one or several heat, electric or magnetic rays, air, gases, mechanical, chemical and any other actions, externally supplied and applied to the mass or flow treated or generated within it, and affecting both the whole mass or flow treated as well as all its molecular and atomic components.
4. And subsequently, to either project and cast the mass or flow treated continuously or intermittently into finished products of any nature, shape and size with or without extra pressure similarly generated within the mass projected into the mold or molds or mechanically applied to the cast mass, the projection into the mold or molds being carried out under airtight conditions, or in a vacuum or with air or other gases.
5. Or to project and extrude the mass or flow treated under the extruding pressure and flowing speed resulting from the combined gyratory and translatory motions it has received and with or without further impact action or mechanical pressure uniformly applied to the cross section by reciprocated and/or rotary tools, into continuous products of any cross section and any length and made of one or more materials, substances, metals or alloys, mixed, or welded or aggregated and extruded in complete or part adherent layers of similar or distinct cross section, the projection and extrusion being carried out, if desired, under airtight conditions or in a vacuum, or in air or other gases.
6. Or to project the mass or flow treated

continuously or intermittently to form coatings or linings or joints of any shape, thickness and size and of any materials, substances, metals or alloys and upon products or parts of any kind and composition to be entirely or partly coated with one or more coatings. The projection can be done in a mold, or by a nozzle and can be airtight, or in a vacuum, or in air or other gases.

More specifically, it is a further object of this invention to apply the following particular processes and to construct machines embodying one or more of the following processes and treatments:

1. *The generation within the flow or mass treated of internal pressure and stresses and of molecular and atomic motions of any kind and magnitude desired.*

This is obtained by using a rotor or distributor of convenient shape, configuration and size in which the mass or flow treated is submitted to rotary and translatory motions of convenient magnitude and acceleration and intermittently or continuously projected into another rotor of any similar or other shape, configuration and size in which the mass or flow projected from the first rotor is submitted to cumulative rotary and translatory motions of greater magnitude, speed and acceleration on a mass or flow already highly worked and under a high acceleration, thus generating greater pressures, stresses and motions in the same direction or not with the first rotor and projecting in the same manner the mass or flow treated in a third rotor and in the same manner in as many rotors as desired to obtain pressures, stresses, speeds, motions, accelerations of any desired magnitude. In any or some or all of these steps, separating, purifying, dissociating, etc. and also casting or extruding of some of the components of the mass or flow treated can take place.

2. *Production of homogeneity*

As a result of the above described process, homogeneity and uniformity of the mass or flow of substances, mixtures, compositions, ores, materials, metals or alloys treated is obtained and maintained after the mass or flow is projected from the first or last rotor on account of the high pressure and internal molecular and atomic motions created which are maintained by the speed and uniform acceleration under which the projection is carried out.

3. *Direct process for applying and distributing internally and uniformly the energy, work and of any magnitude, and regulating characteristics and properties of products*

The mass or flow worked in one rotor can be transferred to the second rotor with practically no loss of the speed, pressure, stress

and molecular and atomic motions and acceleration given to it as well as its temperature and other temporary physical, chemical and other conditions and this highly accelerated mass or flow of worked material is then submitted to additional greater gyratory and translatory motions with greater acceleration with resulting increase in internal pressure, stress and molecular and atomic motions and, in as many rotors as desired, thus submitting the mass or flow treated to cumulative forces, work and effort applied directly to the mass or flow and uniformly distributed to its smallest components and of a magnitude perfectly regulable and reaching limits absolutely unobtainable under present working methods.

In this way, the size, shape, grouping and interlocking of the crystals, particles or smallest components can be efficiently regulated as well as all the resulting physical, chemical, electrical and any other characteristics and properties of the materials, substances, compositions, mixtures, ores, minerals, metals and alloys treated.

If compared with actual mechanical working methods, such as: pressing, forging, hammering, rolling, extruding, die-casting, etc., by which work and effort are mechanically applied externally and superficially to the product treated to reduce its section by breaking or both breaking and sliding of the crystals, when it has a high cohesion and high flowing resistance and offers enormous reaction, it is easily seen that the efficiency is very poor and the effort is never uniformly transmitted to the mass of the product but always superficially and in a decreasing intensity, thus creating distinct stresses within the product which increase the existing stresses thereby resulting of its unhomogeneity and segregation when cast.

The difference between actual methods and this new process is so great that products made by this process, even metallurgical products, are recognizable at a glance from similar products made by actual methods.

If compared with actual centrifugal casting machines making hollow circular castings of concrete or cast iron, it must be pointed out first that these processes and machines do not comprise the steps described under the paragraph describing the general objects of the invention, and consequently have no rotor, but the material needed for one tube for instance, is poured by gravity as it comes from the furnace or the ladle with its impurities, gases and slags, inside of a rotary mold, and the circumferential velocity given to the mold is only sufficient to produce the desired and necessary mechanical action of holding the material against the walls of the rotary mold to mold it while it sets or solidifies, which is generally instantaneous.

Any separation of slag and gases that may take place due to the centrifugal force has for effect to change the even distribution of the metal and to carry it nearer to the inside periphery of the product, making a casting which may be slightly more compact with smaller grain at the periphery than a sand casting but which at the same time is more unhomogeneous throughout.

The circumferential velocities used are generally within the peripheral speed of 10 to 50 feet per second and the centrifugal force maintained between 50 and 100 lbs. per pound of material and with the disposition of the machines and their feeding means this cannot be increased.

In this invention, the speed given to the flow or mass of material projected from the rotor to the molds or extruding dies varies according to the characteristics desired and is easily regulated between the peripheral speed of 100 to 4,000 feet per second or lower with a single rotor and is easily increased to 40,000 feet per second with double rotors and more when desired. The centrifugal force is generally from 600 lbs. to 10,000 lbs. per lb. of material but is easily raised to 80,000 lbs. per lb. of material and much greater when desired when using multirotors.

Under these conditions, not only a much greater internal pressure and stress are generated but all rotors are shaped to produce molecular and atomic motions within the mass, which not only insure a perfect homogeneity unobtainable in any other way, but produce working actions of the highest value, which are much more efficient than all the actual external working methods.

The material which has been purified, made homogeneous, and internally worked under new conditions, is projected under a high pressure and with a very high speed into or through the molds or dies, where if desired additional work can be applied to it whether by rotating the molds or dies or by mechanical pressure.

Furthermore, by combining the rotation of the rotor with one or more secondary rotations of the molds, this process permits the production of castings of any shape, size and dimensions and being either solid or hollow in which the centrifugal force and consequently the internal stress and pressure can be maintained uniformly throughout the whole mass of the casting.

The difference in results between this process and actual centrifugal casting methods is so great that even at a glance the products are differentiated.

4. Purification by separation of undesirable components

It is obtained by generating within the flow or mass treated, adequate intermolecu-

lar and atomic motions creating the necessary sliding, swaging and separating actions between the particles in order to separate and disinterlock the undesirable components and classify and project them according to their particular specific gravity into adequately established separating zones at the periphery of the single or multiple rotors used from which they are continuously or intermittently expelled and eliminated. This applies to molten metals and alloys, molten glass, molten rock, minerals and to mixtures and compositions such as concrete, mortar, etc., and is illustrated in all the rotors shown and described herein and more specifically illustrated in Figs. 5, 9 and 11.

5. Separation into basic components

In the same way as described above any mass or flow of mixed substances, materials, metals or alloys in the fluid, liquid, molten, plastic, or lump state, can be separated into its basic components which can be continuously or intermittently expelled into adequately established separating zones at the periphery of the single or multirotors used.

The separating and eliminating actions can be aided, reinforced and regulated by submitting the mass or flow treated and every one of its molecular and atomic components to the regulated action of compressed air, gas or liquid or powdered substances or electric, magnetic or other invisible forces or action, effectuated in one or various or all the centrifugally created zones of separation of the rotor or rotors used. This is more specifically illustrated in Figs. 5, 9 and 11.

6. Refining or chemical treatment

Under the method described above, it is particularly efficient for refining any mass or flow of substances, material, ore, metals or alloys in the fluid, liquid, plastic, molten or lump state, because it combines with the normal operation of the rotor the continuously maintained and regulated submission of the gaseous, liquid, powdered, plastic or lump reagents to the whole mass or flow treated as well as to every molecular and atomic component, in any proportion desired and continuously maintained and applied in one or several distinct zones of the rotor, with the immediate centrifugal separation and elimination of the slag formed or undesired components and under regulated pressure and stress conditions constantly maintained within the mass or flow treated which also permit to work it under constant temperature and flowing conditions in the different refining or treating zones with the maintenance of a perfect vacuum or of any desired air or gas atmosphere also constantly maintained if desired. This is

more specifically illustrated in Figs. 9 and 11.

7. Smelting and refining of ores or minerals and casting or extruding of the products

In this case the process and machines combine some or all of the following steps which are practically all new and all very favorable for the efficient and economic operation and which improve the quality and characteristics of the metals or minerals extracted.

Continuous and regulated feeding of a mass or a flow of as many components as needed, such as ore, fuel, fluxes, reagents and alloying metals or materials, in a regulated quantity and proportion, whether mixed before or fed separately and afterwards mechanically mixed by the machine within the smelting chamber or zone.

Regulated continuous or intermittent action of air, gases, fuels and reagents on the mixed materials within the smelting chamber or zone, under the internal pressure generated and the internal motions produced to bring all the elements in contact and particularly the ore or mineral treated with the regulated proportion of air, gas or reagent it needs, brought to act on every one of its molecules or particles.

Rapidity, efficiency and economy of the fusion considerably aided by the continuous action of the centrifugal force on the mass or flow treated which aids the disintegration of the solid materials by projecting away every liquid drop as soon as formed and increasing the speed of fusion of the remaining solid components by the shock, washing and catalytic action of the liquid drops while they travel towards the adjacent chamber or zone. In the same way, gases, slags and undesirable components are continuously eliminated outside of the rotor or rotors.

The fused ore or mineral being continuously separated and eliminated as soon as formed from the solid materials within the smelting chamber or zone, permits the maintenance within the chamber of any conditions desired which can all be easily regulated and maintained constant or not, as desired.

The fused ore or mineral projected under centrifugal action into the adjacent chamber or plurality of chambers which can be circular and encircling the smelting chamber or distinct separate channels or multi-channel chambers, can be then submitted to one or more refining operations, continuously or intermittently and in general under the conditions described above in paragraph 6.

The refined product before being projected out of the rotor receive then a final mixing under the accelerated pressure and

internal motions generated into it when at the periphery of the rotor.

The operation can be carried out in several rotors, the first one serving for instance as smelting the fusing chamber and projecting the fused ore or mineral into one or several other rotors in which the refining operations are effectuated under convenient air, gas or reagent action or electric, magnetic or other conditions.

Then the refined material is cast into stationary or rotary molds or containers, into finished castings or in continuous products of any cross section, the projection being done under air-tight conditions or in a vacuum or in air or gas atmosphere.

By this process, the fuel efficiency is higher than that with any actual methods being brought to come in contact and to act on every particle of the ore or mineral, without any physical or chemical interference and with the right amount of oxygen. Furthermore there is no heat transfer losses, no lining, slag, or gas interference and the composition of the fused ore or mineral in each chamber or zone can be at all time under control and regulated. For instance steel of any grade and composition can be obtained directly from any ore and can be alloyed if desired, in a single machine and cast into finished castings having better characteristics than actual forged or pressed products or extruded into rails or beams having better characteristics and properties than actually rolled products. Furthermore, the composition of the smelted product from the ore can be absolutely regulated and kept under much closer limits than that which is obtained from the multiple furnaces and mechanical operations required with actual methods.

In the same way, copper, lead, tin, silver and any other metals can be obtained and cast directly from the ore and also steel of any grade from pig iron, synthetic pig iron from steel scraps, ferro alloys and steel alloys of any composition, glass products of all kinds from glass making minerals, cement from rock bearing cement, etc.

This process is more specifically illustrated in Fig. 11.

8. Electro-smelting or melting of ores, minerals, metals, etc.

In this case the process and machines combines all or some of the steps described under the preceding paragraphs with the additional step of using electric, magnetic, rays, or other physical invisible forces to procure by direct heat action or indirect heat generating or dissociating electrolytic action, the fusion of the mass or flow of materials treated and to further procure, aid, or regulate the separating and refining of the ores, minerals, metals or alloys treated.

This is more specifically illustrated in Figs. 12 and 13.

9. Mechanical homogeneous mixing of substances, minerals, materials and alloying of metals

The process and machines consist in feeding in a rotor or several rotors a mass of flow of several distinct substances or materials or metals of any nature and to submit them to a most energetic mechanical beating and mixing action under an accelerated pressure internally generated and various molecular and atomic sliding, friction, shock and swaging actions resulting from the combined gyratory and translatory motions given to the mass or flow treated, thus creating a complete homogeneity within the mass or flow and maintaining it even after it is projected out of the rotor on account of the internal motions pregenerated which are in no way affected by the speed and acceleration of the projection neither by the centrifugal force. In this way, all the actually known alloys can be obtained under better regulated conditions than within the furnaces or ladles and without any furnace, lining, gas, slags, interference and also vaporization and heat transfer losses.

Furthermore, any number of mixtures between metals which heretofore could not be alloyed or do not produce liquid solutions can be obtained and with any number of metals mixed and alloyed in any proportion under regulated conditions, also other metalloids, minerals, substances can be mixed with metals in the same way in any proportion, giving in every case mixtures or alloys in a perfect homogeneous condition which can be immediately cast into finished castings or extruded into continuous products of any cross section.

In the same way all actually known mixtures and composition of substances, materials, minerals as well as any desired mixture or composition unknown at present, can be obtained perfectly homogeneous and immediately cast either into finished cast products or extruded in continuous products of any cross section.

In this way, concrete beams, columns, tubes and shapes can be extruded with or without metal cores or armatures, or concrete highly compressed and perfectly homogeneous can be cast into wooden or metal forms or molds and also porcelain plates and insulating materials, porcelain insulators, fibrocement and compositions like rubber, ebonite, fibre can be made and cast into finished products or extruded into continuous products of any shape and cross section.

Also alloys or mixtures made of: steel-lead, steel-aluminium, steel-magnesium, steel-chromium, aluminium-magnesium,

zinc-silicium, steel-copper, phosphor-copper, phosphor-aluminium, etc., can be made in any proportion wanted.

This is more specifically illustrated in Figs. 7 and 8.

As shown in Figs. 9 and 10, air, gas or other substances can be blown through the mixture during the mixing and when desired the centrifugal force applied on the materials fed into the rotor can be reduced and the mixture of materials and air or gas, highly mixed and pulverized can be forced and projected through the rotor channel ejecting gates.

15. Continuous or intermittent projection and casting

In this case the process and machines combine some or all of the following steps.

20 The purified, mixed, compressed and homogeneous mass or flow of material, substance, mineral, metal or alloy issuing at the periphery of the single or ultimate rotor, is continuously or intermittently projected outside in a chamber, or a cooling chamber, or a mold, or a plurality of molds. The transfer from the rotor to the chamber, mold or molds can be made air-tight, or in a vacuum, in the air, in another gas atmosphere or in any liquid or fluid materials.

25 The mold, or molds can be made of one or more parts, oscillatory or pivotally mounted or rotary and can be air cooled or water cooled or heated and the mass of material or metal projected into the mold or molds may be subjected to extra pressure generated into it by rotation or other motion of the mold produced by the rotation of the rotor or in connection with it or it 30 can be or not subjected to mechanical pressure in one or several directions externally applied to the casting or to the mold or molds and in sequence or not with the rotor rotation.

35 45 More especially, an object of this invention relates to particular processes and machines in which the mold or molds are rotated with the rotor under the same rotary motion and to machines and processes in 50 which the mold or molds are both rotated with the rotor under the same rotary motion and in addition receive one or more secondary rotary motions and other motions, combining in both cases some or all 55 of the following features and operations:

Use of the centrifugal force or forces generated to produce the following actions: to fill the mold or molds; to eliminate the air contained inside of the mold or molds 60 as well as any gases produced; to eliminate and expel as soon as the mold or molds are filled, all filling gates and feeders in the liquid, fluid or plastic state, to mechanically close the mold or molds whether made of one or several parts; to mechanically apply

a regulated pressure all over the surface of the casting or castings and check the expansion when solidifying or setting or apply mechanically any pressure locally desired; to mechanically open the mold, or 70 molds; to mechanically eject the casting or castings; to mechanically air-cool or water-cool or clean with any fluid the mold or molds; to mechanically place, move, push 75 rotate, expand, withdraw or eject internal or external cores or forming tools or mold parts or inserts in relation with the opening or closing of the molds or with the ejecting of the casting or castings; to generate a uniform 80 centrifugal force and uniform stress within the structure of the castings of any shape, size, dimensions, whether solid or hollow by using one or more secondary rotations and or other motions; and to produce castings composed of several distinct metals, 85 alloys or materials, cast at the same time or in sequence and to joint or assemble the component parts.

Also more specifically, an object of this invention relates to combining with the 90 processes and machines described above, one or more of the following steps and operations.

Continuously operating machines producing castings of one or more materials or 95 metals or alloys, of any shape and size, either in permanent molds or nonpermanent molds which are moved to receive the metals or materials projected from the rotor or rotors by a chain, or wheel or any type 100 of endless conveyor or any other mechanism moving the molds in sequence with the rotation and projection of the rotor and combining if desired any number of mechanical 105 or other operations such as: pressing, forging, hammering, extruding, ejecting, coating, cooling, etc., as well as attaching and removing the molds or cores or parts when 110 convenient and generating one or more secondary rotation or other motions of the mold or molds.

All these steps are new as processes and machines and make the operation of the machines completely automatic under an absolute regulation of all the working conditions which can be maintained constant.

11. Continuous or intermittent projection and extruding

In this case, the process and machines 120 combine some or all of the following steps.

The purified, compressed, mixed and homogeneous mass or flow of materials, substances, minerals, metals or alloys issuing at the periphery of the single or ultimate rotor 125 after passing or not through one or several shaping, reducing or extruding dies and still in the fluid, liquid or plastic state or already completely or partly set or solidified is continuously or intermittently pro- 130

jected outside of the rotor in any desired direction and in a chamber or cooling chamber, or mold or molds, container, or die or dies. The transfer from the rotor to the chamber, cooling chamber, mold die or container can be made air-tight, in a vacuum, or in the air or any desired gas atmosphere, or in any liquid or fluid materials. The mold, molds, dies or containers can be air-cooled, water cooled or cooled by other fluids or can be heated or can have heating devices at the entrance of the material projected from the rotor or at the dies or after extrusion to provide any desired heat treatment.

The extrusion of the finished product is either produced in the rotor under the flowing pressure given to the material treated by the gyratory and translatory motion of the mass and the extruded products are received outside in a stationary chamber or rotary chamber and further cooled, coiled, rolled or straightened.

The extrusion of the finished product is also obtained in projecting continuously or intermittently the material from the rotor into stationary molds or dies in which it sets or solidifies or is shaped if remaining plastic under regulated cooling conditions if convenient and through which it is shaped, extruded and forced out continuously under the kinetic energy stored into it during its passage through the single or multiple rotors aided by the high pressure maintained upon it by the flow continuously or intermittently projected from the rotor adding if desired the shock action of this flow by making the flow intermittent. The extrusion can be further aided and regulated by applying a mechanical pressure at the feeding end of the containers or dies and uniformly distributed over their cross section and the cross section of the die or dies by means of reciprocated tools or both reciprocated and rotary tools or a reciprocated motion of the containers or dies with or without rotary motions.

For materials whose extrusion require a high pressure, it is easily obtained by using the processes and machines described under paragraphs 1 and 2 and furthermore mechanical pressure is also easily added when necessary.

The materials, or substances, or metals or alloys treated are thus cast and extruded into products of any cross section, solid or hollow and of any continuous length, illimitable if necessary and with or without cores or inserts.

12. *Continuous or intermittent projection and extruding of products in layers, part layers or inserts*

All or some of the steps described under paragraph 1 can be obtained in one rotor gy-

rating, working and projecting at the same time distinct substances, materials minerals, metals or alloys, so that these distinct materials projected into different chambers of the same mold container or die can be made to take any desired shape or cross section, forming layers symmetrically distributed one around the other, or only part layers, or layers which are inserted between one or two of the other components and all are separately extruded if desired through partial dies and finally extruded through the finishing die, so that the size and cross section, whether similar of each component is accurately sized before being pressed and welded or aggregated to the other, all the components being finally sized, compressed and extruded under a high pressure that insures perfect welding and adherence between all the components.

The same operation can be accomplished by feeding to the same container distinct materials from distinct rotors, but in every case the projection being made air-tight and in a vacuum and with each distinct component being thoroughly purified, and free from gases and slags and given the characteristics desired in the final product, the welding and adherence are perfectly insured, being made in a vacuum and completed by the extrusion pressure. In this way rails can be made with a wear resisting head made of a material such as chromium welded and extruded with the body of the rail. Rods, shapes, wires or tubular products can be made of two or more metals or alloys. Cement and concrete products can be made of various mixtures or aggregated with other components, etc. This permits the production of a great many new products, which cannot be obtained with the known processes.

13. *Assembling of products of any substances, materials, metals or alloys*

It is further an object of this invention to construct machines providing a new process of assembling and jointing parts of any similar or distinct substances, materials, minerals, metals or alloys.

On account of the fact that the materials treated are given their characteristics and properties by the treatment they receive when in the rotor and these properties and characteristics are equivalent to or much better than those of the actual commercial metallurgical or other products and the characteristics and properties are maintained after the material is projected out of the rotor on account of the high pressure and motions generated within it, this material projected upon any other part of similar or distinct material will set and solidify taking a perfect fit with the former part and forming any assembling or joint

which will be in perfect condition and which will fit in the smallest details of a prepared groove or assembling or jointing shape and having as good characteristics and exactitude as a machined joint or assembling mechanical device with material in as good or better physical and mechanical condition. In this way, rivets can be cast to assemble structures in less time than that which is needed to hammer one rivet. Mechanical parts made of several parts can be successively cast and will be perfectly well assembled. Parts needing an air-tight or water tight joint or any similar joint will have it cast and is much more efficient and more resistant than joints made heretofore due to the quality and contraction of the material when setting and solidifying which can be utilized.

14. *Coating of products with substances, materials, metals or alloys*

It is further an object of this invention to construct machines providing a new process of coating any products with any similar or distinct substances, materials, minerals, metals or alloys.

On account of the facts indicated in the preceding paragraphs and of the facility of obtaining any desired high pressure and internal molecular and atomic motions the material projected from the rotor or rotors permit the production of a very thin, homogeneous and adherent coating of very compact metal or alloy on any metal product or products or other materials or substances and also to obtain homogeneous and perfectly adherent thin coatings of any other substances and materials on products made of any similar and or distinct substances and material. The homogeneity, high tensile strength and elastic limit, compactness, and adherence and durability of these coatings is better than galvanoplastic coatings, gas projected metals, paints, lacquer or any other coating made under actual methods. The coatings can be partial and made in molds or dies regulated to a uniform or variated thickness or can be projected directly upon the products or pieces to be coated by means of nozzles of regulable direction and flow receiving the metal, alloy, material, substance, mixture or composition projected from the rotor. The projection of the coating material can be done under air-tight conditions, or in a vacuum or in air or other gas atmosphere upon products or parts previously cleaned if desired, or heated or cooled.

It is a further object to construct machines which continuously extrude plastic substances, metals or alloys of any cross-section and in poly metals or layers. Such machines may or may not be equipped with heating and melting means for the metals,

and the plungers or the mold or bath may be reciprocated to form the extruded product.

The gyrocast and gyroextruded metal products according to the present invention are differentiated at a glance from similar products actually made and laboratory tests show their highly improved characteristics.

They are perfectly homogeneous throughout in metal structure, chemical composition, crystal size, strength, etc. and they show no internal stresses neither interlocked blowholes, pipes, slags or gases.

They show a thin grain structure which is the same and absolutely uniform throughout the whole mass of the products. The size of the crystals is considerably smaller than the crystals of the same metals cast in metal or sand molds or centrifugal casting machines and the size can be made smaller than crystals broken down under the most powerful mechanical action now obtainable. The kind, class, shape and assembling of the crystals is or can be made different from that which is at present shown by the same metal.

All the physical, mechanical and chemical properties are modified and considerably improved, as well as the electrical and magnetic characteristics as may be shown by comparative tests.

It is a further object of the present invention to construct machines which will not only produce products and castings but will also produce the metal molds and dies used thereafter to make such specific products and castings.

The molds and dies produced by this method have the advantage of being made of common nonexpensive metals and are permanent or at least extraordinarily long lasting even when working liquid steel, iron copper or bronze, on account of their special metal structure, extremely high elastic limit and undestructible surface. They don't burn or crack and no facing or refacing are needed.

These molds and dies are not made from solid metal which has been cast or forged and which is afterwards machined and cut, but from liquid metal worked in the liquid, plastic and solid states by the process and they reproduce the models desired with every fine detail, engraving, sharp angles, etc. with a neatness and accuracy which is never obtained even with the most costly machined molds. Furthermore molds and dies of the same models can be produced in large quantities and without the slightest variation between themselves.

The cost of production of these metal permanent molds and dies, is as small as the actual foundry cost of castings of the same metals hand molded in sand.

When desired permanent molds made of non metallic materials are also made by this process and the molds obtained are more accurate and considerably more lasting than 5 actually made permanent molds.

The arrows on the drawings indicate the path of the material or materials or metal through the machine and also the path of the gases and slag and other fluids.

10 Figs. 1 to 8 show various forms of rotors or rotary distributors for gyrating and projecting a mass or flow of one or various substance, mixture, composition ore minerals, metal or alloy into or through a mold or 15 molds or die or dies on outside as finished product or upon any products or articles as coating or lining. The speed of rotation of the rotor or distributor is dependent upon the size of the specific machine and the specific work it has to produce. Furthermore, the speed of rotation, that is the peripheral speed of the rotor, may be varied in order to produce any desired internal pressure and stress and specific intermolecular and atomic 20 motions of the material treated to impart certain characteristics and properties to the specific material used and into the product obtained. In the form of rotor shown in Figs. 1 and 2 three radial and cone shaped 25 passages 2' are provided in the base portion 1, these passages preferably being arranged angularly in a slightly downward direction. The top portion 2 is secured to the base portion by means of bolts 3 and the material or 30 metal is fed through a central charging passage 3'. A number of cone-shaped slag or gas passages 12 are arranged in the top portion, preferably one for each passage 2'. These slag passages are adapted to carry off 35 the gases and slag or other impurities which are forced out of the mass or flow of material or metal when rotated and projected, due to the high pressure generated and sliding and separating intermolecular and atomic 40 motions created by the shape of the channel. The process carried out by this rotor is as follows: The metal or material is fed into the rotor and, due to centrifugal force, it is forced radially into the passages 2'. 45 Due to the increasing acceleration and increasing speed and internally generated pressure, stress, and sliding, friction, and separating motions given to the molecular, particles and atoms, the lighter components, 50 gases, slags, etc. are separated and expelled in the passage 12 and the purified material or metal or alloy is then mixed by the same internal motions and expelled under an accelerated high pressure centrifugally generated. The rotor or rotors may have their axle of rotation arranged vertically, horizontally or at any angle, the operation not being affected thereby.

Figs. 3 and 4 show a similar distinct rotor in which the passages 2' are curved in-

stead of straight. The functions and operation, however, are the same. These passages may be circular or spirally arranged to give any particular internal motion or motions desired and any suitable number may be provided. The rotor is shown mounted on a spindle 4 which may be rotated in any usual way.

Fig. 5 shows a machine for the centrifugal separation of a liquid alloy or other mixtures, or compositions into several components according to their specific gravity and the projection under centrifugal force of the separated components into distinct receptacles or molds. The rotor has a base portion 1 mounted on the spindle 4 and the top portion 2 is secured on the base by the bolts 3. At the upper center portion of the base a valve 7 is provided which cooperates with the feeding hopper 8. By suitably raising or lowering the feed hopper the amount of metal or mixture flowing from the hopper may be regulated by increasing or decreasing the distance 8' between the hopper and the valve or it may be entirely shut off. In this modification a third portion 5 is secured on the base and around the top portion by means of bolts 6. The first separation of a component of the alloy may take place through passage 12 into the receptacle 10 and a second separation through the second passage 12 into receptacle 9. Rods or supports 11 are provided for supporting the receptacle 9 which in turn supports the receptacle 10.

The machine shown in Fig. 6 is for the purpose of forming and extruding a set or solidified product made of two or more layers of metal, material or substance separately shaped and of any cross section or to shape and project a flow of liquid, fluid or plastic materials, metals and substances of any cross section. The portions 1 and 2 of the rotor are as usual bolted together by bolts 3 and the base portion 1 is provided with a valve 7 which cooperates with the hopper 17. A second hopper 16 is provided which is adapted to feed a second metal or material into the passages 2' of the distributor. By vertically adjusting the support rods 11 the hopper 16 may be adjusted by means of the ring 18, the flow of metal or material being regulated by the distance between the outlet 16' and the top portion 2. By this operation the hopper 17 is also adjusted. Slag passages 12 are provided in the top portion 2. In operation one metal or material is fed into the hopper 17, the outlet thereof being controlled by the valve 7. The metal or material then flows into the passage member or sizing or extruding die 14' which is mounted in sleeve 13, and, due to the rotation of both of these members, the metal is subjected to a centrifugal pressure, thereby being extruded through 130

the die 14 in the end of the passage member. At the same time that a metal or material is fed from the hopper 17 another metal or material is also fed from the hopper 16 and, since both hoppers are regulated simultaneously, the flow of metal will be of the desired uniformity. The metal or material from hopper 16 flows around the passage member 14' and unites with and is welded or aggregated with the metal extruded from die 14. Due to the rotation of the rotor the metals or materials are both subjected to the centrifugal force which separates all slag and gases and welds or aggregates the two metals or materials or one metal and one material together. Due to the high pressure the metals and materials are extruded through the die 15 into the final product or projected into a continuous flow of poly metal, alloys or materials. In the same way more than two metals or materials can be worked, shaped and extruded or projected.

The machine shown in Figs. 7 and 8 is similar to the machine according to Fig. 6, except that in this machine the metals, materials or substances are adapted to be mixed in order to obtain new alloys or other mixtures. The metals or materials are fed into the hoppers 16 and 17, which are adjustable, the hopper 17 by the valve 7 and the hopper 16 by the top portion 2. The metal or metals or materials fed into the hopper 17 flows into the sleeve 13 and out through one or more openings 13' into the passages 2' in the rotor. The second metal or material meets the first in the passages 2' and the two or more metals or materials are forced radially in the passages, due to centrifugal force. The pressure created and the molecular and atomic motions generated under the combined gyratory and translatory motion given to the flow purifies and mixes them and the slag and gases are forced through the passages 12. In order to increase the mixing a plurality of breakers 19 are provided in the passages 2' and as the metals or materials are forced around these obstructions a thorough mixing takes place, aided by the motions created within the mass or flow and under a high centrifugal pressure. The mixed metals or alloys or materials are then projected at the ends of the passages 2' and, if it is desired to cast immediately, molds or dies can be provided or the alloy or mixture can be projected to form coatings or linings. The mixture can comprise one or more metals or one or more liquid metals and powdered materials or plastic materials or powdered metals or metalloids, such as carburizers, deoxydizers, fluxes, etc. This machine will therefore produce all known alloys, forming and regulating the alloying mechanically, and with better alloying conditions under pres-

sure, and with shock, friction sliding and swaging intermolecular and atomic actions. Also metallic mixtures or alloys may be obtained which have heretofore been unknown for the reason that they did not form liquid solutions under the known processes which, however, can be mixed by the process in all proportions and any number of them at the same time, and under close mechanical regulation. The new alloys are homogeneous and mixtures between metals and metalloids or other substances in any proportions may be obtained. Alloys are further obtained in conditions which exclude all action from gases, fuel, slag and furnace linings, since they are made directly and extemporaneously in the machine. Also in transferring the alloy from the rotor to the mold or die no heat is lost and it is carried on entirely out of contact with air. This type of rotor and machine performs all the operations and carries out the processes described in the same of the introductory paragraphs.

In Figs. 9 and 10 a modified form of rotor is shown showing more specifically the refining or chemical treatment of any metal, alloy, material or substance. The material which can be molten iron for instance is fed into the hopper 24 from which it flows into the passages 2' past the valve 7. In this form the base portion 1 and the top portion 2 of the distributor are provided with a plurality of channels or tuyères 20 and 21 arranged vertically. Mounted on the spindle 4 is a fan 22 which rotates therewith and immediately above this fan and under the base portion of the rotor is a chamber 26 into which open the channels 20. The base 23 is adapted to have the fan casing mounted thereon. When the machine is in operation, the air sucked by the fan enters channels 21 and then filters through the molten iron which is being forced by centrifugal pressure radially in the passages 2'. The air after passing through the iron passes into channels 20 and into chamber 26 from whence it traverses through the fan and out through outlet 27 in the fan casing. The iron will thus be converted into steel similar to the process carried out in a Bessemer or Thomas converter. In order to aid the flow of the metal and to insure complete treatment of all particles of iron guide members 25 are radially arranged in the passages 2'. The direction of the air flow could be reversed and an external source of air or gas or gas mixed with powdered or fluid reagents can be provided, such as a compressor or other suitable machine. The main object is to submit the material passing through the rotor to air, gas or any other fluid or substance. The production of steel from liquid iron, the transformation being made within the distributor is con-

tinuous and instantaneous, and by this process produces a better steel and operates more efficiently, since every atom of iron receives the proper amount of air in order 5 to oxidize its carbon, and by the control of the air any grade and class of steel can be obtained. The efficiency is increased by working under pressure and due to the sliding, separating and swaging intermolecular 10 and atomic actions within the flow of molten iron. Such gases as CO and CO₂ and also slags are eliminated as soon as formed and the compressed and refined steel formed may be immediately cast or extruded into 15 finished homogeneous products, if desired, without heat transfer losses. Also, synthetic iron may be obtained by incorporating carbon, silicon, manganese or other elements in fluid or powdered form to the 20 liquid steel in hopper 24, or vice versa. Similarly any other metal or substance or mineral or material can be treated with a gas, fluid or substance in order to obtain a specific material. When a mixture and projection of both the materials fed and air or gas or lighter substances blown is desired, 25 centrifugal force applied on the materials can be reduced and the mixture forced or projected through the channel ejecting gates. 30 In the modification according to Fig. 11, the hopper 34 separated by four partitions 34' is adapted to receive ore or minerals in one chamber and granulated or lump coke or any liquid or plastic or lump fuel, fluxes 35 and deoxydizers or reagents in the other chamber. Other materials can be used, depending upon the specific physical or chemical treatments desired. In the present example, iron or copper ore or glass making 40 minerals are used and by means of the valves 35 the rate of feeding of the materials can be regulated. As these materials descend in chamber 32' they are heated and smelted or fused, the gases being driven off through 45 openings 32 and the slag through openings 31. The slag thus collects in the receptacle 33 and may be carried off through outlet 33'. In order to supply a strong current of air for the smelting operation, air is supplied under pressure by any suitable means 50 through valve 30 into chamber 29, and from there flows upwardly into and through the rotor 28 through openings 28' therein. The iron or copper ore after being smelted to 55 iron or copper is forced radially in the passages 2' of the rotor due to the centrifugal force thereof. As in the modification according to Fig. 9 the iron will be transformed to steel with any desired refining action, due to the action of the air as it is forced radially in the passages. The rotor can be water jacketed or can be provided with fins or blades for air cooling. Air or other gases or fluid or even lumps 60 or pulverized fuels or materials or substi-

tutes can be blown through the materials fed by the tuyère box and suitable tuyères can be distributed in the fusing zone, in the separating zone and in the refining zone. The materials are fed by gravity in the internal chamber where they are melted under centrifugal action which operates to separate the fused metals or minerals and slags from the solid materials. The entire treatment completely refines the metal or mineral which is ultimately projected continuously or intermittently out of the rotor blast furnace into molds, dies or ingot molds. This same process can be applied for melting any other ores or minerals or the rotor 70 blast furnace can be used as a cupola feeding through hopper 34 cold solid pieces of pig iron and coke and other materials. In this machine steel can be obtained directly from iron ore and the composition of the 75 steel can be closely regulated. Pure copper can also be obtained directly from ore and other metals or minerals can also be obtained in the same way. This machine can also be used as a separator for any fluid, 80 plastic, powdered or lump material fed, by means of combined centrifugal and air separation, the air taking away the lighter materials in the different zones of separation, 85 dividing the initial material loaded in two 90 or more different classes according to their specific gravity and insuring continuous separation and elimination of the products separated and under the same working conditions. The slag and gas escape openings in 95 the chambers 36 and 32' can be increased in number or reduced, depending upon the specific materials to be worked and further can be arranged at different levels in order to create zones corresponding to the materials used in depending upon the treating 100 materials to be fed into the machine. 105

Fig. 12 shows a modified rotor furnace in which the metals or materials fed are melted under centrifugal action. The electric resistance or heating coil 87 is mounted on the top portion 2 of the rotor, the current connections being indicated by collector brushes and a commutator 38. A cover 44 is provided which may be utilized to close 110 the feeding end and thus the melting of the ore or metal or mineral can take place in an air-tight furnace. Vacuum can be set up by pumping air from the furnace 39 by means of a tube 40' in the cover and this same 115 tube can be utilized to pump neutral gases or other gases or fluids in the furnace which are necessary for certain chemical actions. Slag and gases are as usual driven off through the openings 12 in the top portion 2. The 120 melting efficiency is increased by the centrifugal action which separate the liquid particles as they are formed and further disintegrates the still solid material which is 125 aided by the shock of liquid particles on its 130

surface and the washing action of the liquid material on the solid particles.

Air or other gases or liquid, or plastic or powdered materials can be forced through 5 the rotor furnace similarly to Fig. 11 if convenient and the electric connections can be used to set an electrolytic action within the metal or material treated in the fusing zone or within the refining zones. Also instead 10 of mechanically gyrating the metal or alloy or material treated by rotating the rotor, it is possible to have the rotor stationary, but to generate a rotary motion and projecting motion within the mass or flow treated by 15 electromagnetic action giving to the coil an adequate disposition, thus having the rotor furnace stationary but the metal or alloy melted, worked and projected under the centrifugal action due to the rotation of the 20 metal or material, in the same way and conditions as with mechanically rotated rotors.

Fig. 13 shows a distributor which includes an electric generator operated by the same shaft which rotates the distributor to thus 25 produce its own current for melting the metal or materials fed into the hopper 39 under arc, resistance, high frequency or any electro-magnetic action. As shown the hopper 39 is surrounded with an electrical resistance unit 37 to which current is fed by 30 the generator. A coil 41 is mounted around the resistance and on the top portion 2 of the distributor, said coil being adapted to rotate. The stationary coils 43 of the generator are mounted in the casing 43' which 35 is supported by means of supports 11 secured to a cross piece 18 to which the casing is secured. The commutator 42 of the generator is designed and mounted in the usual 40 way. The current produced by the generator may be utilized for producing an arc or induction furnace or high frequency furnace in which case the resistance unit can be dispensed with.

45 The feeding hopper 34 shown in Fig. 14 has one or more partitions therein for feeding several different materials and may be heated by means of suitable heaters or burners 47. The valve 45 for feeding the materials may be shut off or may be adjusted by means of lever 46. An electrical resistance can be used instead of the burners or any other means can be employed, such as thermic chemical reactions.

50 The feeding hopper 34 of Fig. 15 shows an arc resistance furnace in which the carbon electrode 49 is adjustably mounted by means of lifting lever 50. By moving the electrode 49 toward the metal rod 48 or scrap 55 52 which comprises the other electrode, an arc will be set up which will melt the metal which in such condition will run through the passage in the electrode 49. The hopper 34 is preferably lined with some suitable material as shown by lining 51. By this ap-

paratus cold steel scrap of suitable chemical composition or any other materials can be loaded cold and continuously or intermittently melted to supply the molten materials to the rotor and to the molds or dies. 70 In this way cold scrap can be transformed into new castings as soon as melted and with the best heat efficiency, and eliminating all conductivity and transfer losses. A cover, with or without outlet tubes, can be applied at the top of the hopper. Carburizers, alloying or other materials can be introduced into the hopper in order to change and regulate the composition of the molten material as desired. 80

In Figs. 16 to 18 is shown an intermittent gyratory casting machine in which the rotor and the mold or molds are rotated, the mold or molds are jointed and the metal or materials cast, the machine stopped 85 and the castings ejected from the molds. The process is then repeated. In the specific construction of the machine any type of rotor can be used and these rotors 1 and 2 are surrounded by a mold which is in two 90 parts, the part 53 being secured to base portion 1 of the distributor and part 55 secured to and movable with the top portion 2. The base portion 1 of the distributor is mounted on a rotor 54 into which a spindle projects 95 for rotating the machine. A ring 62, connected by nuts with the movable bolts 56, moves the ejecting pin 64 back and forth for the purpose of ejecting the casting, after the mold parts have separated. The mold 100 parts 53 and 55 are held in closed position by centrifugal force acting on the counterweights 60 mounted on the pivoted levers 59 and held in place by the nuts 61. This lever 59 is operatively connected with the 105 bolts 56, so that upon actuation of the lever 59 the bolt will be operated to open or close the mold parts. When the machine revolves the centrifugal force tends to force the counterweight levers in a horizontal position, thus tightly closing the mold parts. 110 The metal or alloy or material or materials is now poured into the hopper and is projected by centrifugal force from the rotor into the molds. After the metal or material 115 is poured, a greater speed may be imparted to the machine, thus generating greater centrifugal force, which tends to check the separation of the mold parts and consequently the expansion of the castings, as the 120 metal or material passes from the liquid to the solid state. When the machine is stopped the counter weights will operate the bolts, thus separating the parts of the mold, at the same time operating the ejecting pins 125 in order to eject the castings from the mold. These machines can mold any shaped castings and can also mold castings requiring cores. A passage may be provided in the upper half of the mold through which air, 130

- slag, gases and excess metal may discharge itself. The feeding gate is thus cut off by centrifugal action when the metal or material is liquid or fluid, thus producing 5 finished castings without any gate or feeder which must afterwards be cut off, and further castings are produced, which are free of any fins, due to the high centrifugal pressure which closes the mold.
- 10 A number of molds of the same shape or of different shapes can be provided in the machine of Figs. 16 to 18, as shown in Fig. 19, for instance.
- Figs. 20, 21 and 22 illustrate a centrifugal 15 pressure casting machine for making plow shares but any other suitable shape can be molded therein, and any number of molds may be provided. In such machines the molds are secured to any convenient type 20 of rotor 1 and 2, the inner half 69 being pivotally secured thereto. The outer half 68 is secured at the outer end to an arcuate member 67, said member being mounted on the spindle 4 to rotate therewith. The 25 inner half 69 of the mold is pivoted at the rotor end so that when the machine is stationary this half will assume the dotted line position, so that the casting may fall from the mold or may be easily removed. Upon 30 rotation of the machine the part 69 will be swung outwardly meeting the part 68 and thus by centrifugal force the parts will remain tightly closed during which time the casting will take place. An increase of the 35 speed as soon as the metal or material is poured will place an additional pressure upon the casting by the centrifugal force generated, thus causing a very efficient and added pressure upon the casting while it 40 passes from the liquid to the solid state. A passage 68' may be provided in the outer portion 68 of the mold in order to eliminate the extra metal and gates. In Fig. 21, the outer half 68 of the mold is shown and a 45 cross section thereof showing the casting 71 and Fig. 22 illustrates the inner half 69 showing a cross section thereof and the casting 70.
- Fig. 23 shows a complete gyratory pressure casting machine in which the spindle 4 is mounted in ball bearings, as for instance 83, in the support 86 and is driven by means of a pulley 85 by any suitable motor. A clutch mechanism 84 is provided 55 in order to start and stop the machine for the purpose of the removal of the castings. The clutch is operated by a lever 87' which in turn is operated by lever 87. At the lower end 88 of this lever an operating lever 88' 60 is pivotally secured thereto, the actuation thereof being adapted to operate the clutch and also to operate the brake 82 which bears on ring 81 and which is actuated by the lever 82'. The object of this brake is to change 65 the rotary speed and to stop the machine in a short time in order to increase the efficiency and speed of operation thereof. The rotor containing the top portion 2 and the base portion 1 which can be any of the different types of rotors shown separately is mounted 70 on the spindle and a ring 77 is mounted on the base portion and rotates therewith. This ring forms an abutment for the plurality of molds 72 and 73 which are pivotally mounted on the base portion by forks 75. 75 These molds may have any desired cross section depending upon the casting to be produced, and when the machine comes to a stop the molds will assume the dotted line positions, so that the casting will fall therefrom. In operating this machine a rotation of the various parts will force the mold to assume the full line position, due to centrifugal force, whereby the ends of the molds will be closed by the ring 77. The metal or material is then poured and cast and then the machine is stopped whereby the molds will assume vertical positions and the castings will fall from the molds aided if desired by centrifugally operated ejectors, not shown. 80
- 85 The mold 72 is for the purpose of making bolts or similar castings, the head being molded in the ring 77 as shown. The mold 73 is made in three pieces in order to produce castings having different directions. 90
- The upper part 78 of mold 73 is stationary and secured by screw 79 but the lower part 76 is pivoted as shown. Fig. 24 shows a modified machine in which the ring 77 is stationary and is supported by supports 11 100 secured in plate 23. This plate 23 is secured and supported on the support 86. The mold 72 is rotatably mounted in the fork 75 by means of ball bearings 89 and rotates with the rotor and receives a particular secondary rotation by frictional contact with the ring 77. Due to centrifugal force the mold assumes the position shown in Fig. 24, thus closing the end thereof and at the same time causing axial rotation of the mold which subjects the metal in the mold to a further centrifugal pressure. The mold according to Figs. 25 and 26 is similar to the mold of Fig. 24, except that in addition an inside member core or cores or tool 91 is provided 105 which is secured to the feeding mouth 90 in the fork 75. This member produces a rolling and equalizing action on the inner surface of the casting and also regulates the thickness of the casting. No excess metal 110 can be molded and compressed between the mold and the member 91, the excess metal being expelled out of the mold.
- The gyratory pressure casting machine according to Fig. 27 may have two or more molds which receive secondary rotation. The mold 72 on the left side of the machine is pivotally mounted on a support 75 which is mounted on and rotates with the spindle. 120 At the lower end of the mold a contact mem- 125

ber 103 is provided which is adapted to contact with the stationary ring 77 mounted on rods 11 when the machine is rotated, and the ends of the molds are thrown outwardly 5 by centrifugal force. The metal or alloy or material is purified and compressed in the rotor, the air, gases and excess metal being expelled centrifugally as in all of the other machines. The mold construction shown on 10 the right side illustrates a ring 77 mounted on a stationary part of the machine.

I claim as my invention:

1. A centrifugal pressure distributor for metals and alloys, comprising a rotary portion 15 having walls forming radially arranged passages therein which are adapted to subject the metal to a high pressure upon rotation thereof and to project the metal radially from the passage at the periphery of 20 the portion and to impart intermolecular motion thereto, said portion also having passages therein communicating with the first-named passages for slag and gases which are forced out of the metal.

25 2. A centrifugal pressure distributor for metals and alloys, comprising a rotary portion having walls forming radially arranged passages therein which are adapted to subject the metal to a high pressure upon rotation thereof and to project the metal radially 30 from the passage at the periphery of the portion, said portion also having passages therein which are arranged at right angles to and in communication with the first-named passages to convey the slag and gases 35 forced out from the metal.

3. A centrifugal pressure casting machine for substances, metals and alloys, comprising a rotary distributor having a central 40 charging passage for the substance and radially arranged passages therein, each converging toward the periphery of the distributor and which are adapted to subject the substance to a high pressure, purifying and 45 mixing action upon rotation thereof; a ring associated with the distributor; and a mold secured at one end to the distributor at the peripheral end of each passage into which the substance is projected from the passage 50 and cast in the mold, said mold contacting with and being restrained at the other end by the ring.

4. A centrifugal pressure casting machine for substances, metals and alloys, comprising 55 a rotary distributor having a central charging passage for the substance and radially arranged passages therein which are adapted to subject the substance to a high pressure upon rotation thereof, said distributor 60 also having passages therein for the escape of the impurities from the substance in the radial passages; a ring associated with the distributor; a mold secured at one end to the distributor at the peripheral end of each radial passage into which the substance is pro-

jected from the radial passage and cast in the mold, said mold contacting with and being restrained at the other end by the ring; a spindle for the distributor; and means for rotating and controlling the spindle.

5. A centrifugal pressure casting machine for substances, metals and alloys, comprising a rotary distributor having a central charging passage for the substance and radially arranged passages therein which are adapted to subject the substance to a high pressure upon rotation thereof; a ring associated with the distributor; and a mold having a portion pivotally secured to the distributor and the other portion secured at 70 one end to the ring whereby upon rotation the pivoted portion of the mold will be urged outwardly, due to the centrifugal force, to close the mold and to receive the substance which is projected from the peripheral end of the passage and cast it in the mold.

6. A centrifugal pressure casting machine for substances, metals and alloys, comprising a rotary distributor having a central charging passage for the substance and radially arranged passages therein which are adapted to subject the substance to a high pressure upon rotation thereof; a stationary ring associated with the distributor; and a mold secured to the distributor at each peripheral end of each passage whereby upon rotation of the distributor the substance will be projected from the passage into the mold to cast the substance, the mold being adapted to rotate due to contact with the ring to impart a further pressure upon the substance and casting.

7. A centrifugal pressure casting machine for substances, metals and alloys comprising a rotary distributor having a central charging passage for the substance and radially arranged passages therein which are adapted to subject the substances to a high pressure upon rotation thereof; a stationary ring associated with the distributor; a fork mounted adjacent each passage; and a mold rotatably mounted in each fork adapted to receive the substance projected from the peripheral end of the passage to cast the substance, said mold upon rotation of the distributor being forced outwardly by centrifugal force thus contacting with the ring which imparts a rotary motion to the mold to impart a further pressure upon the substance and casting.

8. A centrifugal pressure casting machine for substances, metals and alloys comprising a rotary distributor having radially arranged passages therein which are adapted to subject the substances to a high pressure upon rotation thereof; a stationary ring associated with the distributor; a fork mounted adjacent each passage; a mold rotatably mounted in each fork adapted to receive

the substances projected from the peripheral end of the passage to cast the substance, said mold upon rotation of the distributor being forced outwardly by centrifugal force 5 thus contacting with the ring which imparts a rotary motion to the mold to impart a further pressure upon the substance and casting; and means in the mold for forming and working the casting.

10 9. A centrifugal pressure casting machine for substances, metals and alloys comprising a rotary distributor having a central charging passage for the substance and radially arranged passages therein which are adapted 15 to subject the substance to a high pressure upon rotation thereof; a mold associated with the peripheral end of each passage adapted to receive the substance projected from the peripheral end of the passage to 20 cast it in the mold; means for rotatably mounting said mold on the distributor; a stationary ring associated with the distributor upon which the mold receives its rotary motion to impart a further pressure upon the 25 substance and casting; and a feeding mouth secured to each mold which is adapted to distribute the projected metal and having passages therein for the escape of slag and gases.

30 10. A centrifugal pressure casting machine for substances, metals and alloys comprising a rotary distributor having a central charging passage for the substance and radially arranged passages therein which are adapted 35 to subject the substance to a high pressure upon rotation thereof; a spindle for the distributor; a mold for each passage pivotally and rotatably mounted on the spindle; a stationary ring associated with 40 the distributor; a contact member mounted on the mold adapted to contact with the ring in order to impart a rotary motion to the mold upon rotation of the spindle; and a feeding mouth secured on the distributor 45 at the peripheral end of each passage adapted to distribute the projected metal in the mold.

11. A centrifugal pressure casting machine for substances, metals and alloys comprising 50 a rotary distributor having radially arranged passages therein which are adapted to subject the substance to a high pressure upon rotation thereof; a spindle for the distributor; a mold for each passage 55 pivotally and rotatably mounted on the spindle; a stationary ring associated with the distributor; a contact member mounted on the mold adapted to contact with the ring in order to impart a rotary motion to 60 the mold upon rotation of the spindle; a feeding mouth secured on the distributor at the peripheral end of each passage adapted to distribute the projected metal in the mold; and means in the mold for forming 65 and working the casting.

12. A centrifugal pressure distributor for substances, metals or alloys for casting machines comprising a rotor having walls forming a cone-shaped passage therein and a charging opening, said passage being 70 adapted to subject the substance to a high pressure upon rotation of the rotor, and said rotor having means for forcing any impurities in the substance out of the passage.

13. A centrifugal pressure distributor for substances, metals or alloys for casting machines comprising a member having a passage therein and a charging opening, said passage comprising converging walls adapted 80 to subject the substance in the passage to a high pressure upon rotation of the member, and said member having means for forcing any impurities in the substance out of the passage.

14. A centrifugal pressure distributor for substances, metals or alloys for casting machines comprising a rotor having walls forming a passage therein and a charging opening, said passage being radially arranged and which converges toward the periphery of the rotor to subject the substance to a high pressure upon rotation of the rotor, and said rotor having means for forcing any impurities in the substance out 95 of the passage.

15. A centrifugal pressure distributor for substances, metals or alloys for casting machines comprising a converging passage member which is adapted to be rotated to subject the substance to a high pressure and having a charging opening, said member having means for forcing any impurities in the substance out of the passage.

16. A process for casting substances, metals or alloys by centrifugal pressure which comprises in placing the substance under a high centrifugally-generated pressure to purify, mix and compress the substance; extruding the substance due to the pressure into a mold; and subjecting the mold to double motions to subject the substance to additional pressure to form the casting.

17. A centrifugal pressure distributor for substances, metals and alloys comprising a member having a radially arranged passage and a charging opening and a plurality of channels through the member and the passage; and means for forcing air through the channels to treat the substance traversing the passage upon rotation of the member.

18. A centrifugal pressure distributor for substances, metals and alloys comprising a member having a central charging passage for the substance and radially-arranged passages therein, and a plurality of channels through the member approximately at right angles to the passages; and means for forc-

ing air through the channels to treat the substance traversing the passage upon rotation of the member.

19. A centrifugal pressure distributor for substances, metals and alloys comprising a member having a central charging passage for the substance and radially-arranged passages therein, and a plurality of channels through the member approximately at right angles to the passages; and a fan for forcing air through the channels to treat the substance traversing the passage upon rotation of the member.

20. A centrifugal pressure distributor for substances, metals and alloys comprising a member having a central charging passage for the substance and radially-arranged passages therein, and a plurality of channels through the member approximately at right angles to the passages; a spindle on which the member is mounted and from which it receives rotation; and a fan mounted on and adapted to rotate with the spindle to force air through the channels to treat the substances traversing the passage upon rotation of the member.

21. A centrifugal pressure casting machine for substances, metals and alloys, comprising a rotary distributor having a central charging passage for the substance and radially-arranged passages therein which are adapted to subject the substance to a high pressure upon rotation thereof, and a plurality of channels through the distributor approximately at right angles to the passages; a ring associated with the distributor; a mold having a portion pivotally secured to the distributor and another portion associated at one end with the ring whereby upon rotation the pivoted portion of the mold will be urged outwardly, due to the centrifugal force, to close the mold and to receive the substance which is projected from the peripheral end of the passage and cast it in the mold; and means for forcing air through the channels to treat the substance traversing the passage upon rotation of the distributor.

22. A process for centrifugally casting metals comprising subjecting the metal to a centrifugally-generated pressure; forcing air through the metal; and casting the metal under the action of the centrifugally-generated pressure.

23. A process for centrifugally casting metals comprising subjecting the metal to a centrifugally-generated pressure; forcing air through the metal; casting the metal under the action of the centrifugally-generated pressure; and subjecting the cast metal to a further centrifugally-generated pressure.

24. A centrifugal pressure distributor for substances, metals and alloys, comprising a

rotor having a central charging passage for the substance and a plurality of walls therein, converging toward the periphery of the rotor, forming passages; and a plurality of walls forming passages arranged at approximately right angles to the first-mentioned passages for the slag and gases; and means for rotating the rotor to subject the substance in the first-mentioned passages to a high pressure and force the slag and gases therefrom through the second-mentioned passages.

25. A centrifugal pressure casting machine for substances, metals and alloys, comprising a rotary distributor having a central charging passage for the substance and radially-arranged passages therein which are adapted to subject the substance to a high centrifugally-generated pressure; a ring associated with the distributor; and a two-part mold for each passage secured at one end to the distributor and one part at the other end contacting against the ring, the other part of the mold being adapted to close against the other part by means of centrifugal force upon rotation.

26. A centrifugal pressure casting machine for substances, metals and alloys, comprising a rotary distributor having a central charging passage for the substance and radially-arranged passages therein which are adapted to subject the substance to a high centrifugally-generated pressure; and a two-part mold for each passage secured at one end to the distributor, one part of the mold being fixed on the distributor and the other part being adapted to close against the first part by means of centrifugal force upon rotation and to fall away from said part upon non-rotation.

27. A process for centrifugally casting metals, comprising subjecting the metal to a centrifugally-generated pressure and at the same time forcing air through the metal.

In testimony whereof I affix my signature. JOSEPH MERLE.
